TELEVISION PHOTO MACHINE

Leon S. Gross, 2210 N. Graham St., Philadelphia 51, Pa.

Filed Nov. 27, 1964, Ser. No. 82,808

Term of patent 14 years

(Cl. D61—1)

FIG. 1 is a perspective view of a television photo machine, embodying my new design;

FIG. 2 is a front elevation of the television photo machine illustrated in FIG. 1, this figure and the subsequently described figures being at a reduced scale relative to FIG. 1;

FIG. 3 is a side view of the television photo machine illustrated in FIGS. 1 and 2 but showing the side opposite to that illustrated in FIG. 1;

FIG. 4 is a back view thereof; and

FIG. 5 is a top view thereof.

The essential features of my design are shown in full lines.

I claim:

The ornamental design for a television photo machine, as shown and described.
